RAILWAY TRACK SWITCH

Charles L. Wilmot, Pittsburgh, Pa.

Application July 29, 1938, Serial No. 221,879

3 Claims. (Cl. 246—430)

This invention relates to new and useful improvements in railway track switches, the primary object of which is to provide a switch structure of substantially the same rigidity and stability as the remaining part of the track structure.

Another object of the invention is the provision of a railway track switch unit which shall be self-contained and mounted on a casting which is designed to fit upon the track bed in cooperative relation with the rail ties.

A further object of the invention is to provide a railway track switch in which the switch points are eliminated and which is housed to eliminate access of snow, ice, dirt or other substances or particles and in which the operating parts are protected from the corrosive action of the elements.

Still another object of the invention is to provide a railway track switch which shall be adapted to be secured against displacement by locking means operative by the switch throwing mechanism, all of the foregoing objects and improvements being for the betterment of the switch mechanism generally, resulting in a safer switch construction, permitting train operations at higher speeds than heretofore possible and which will substantially reduce maintenance cost and the operating difficulties incident to the conventional type of switch.

These and further objects of the invention will become more apparent from a consideration of the accompanying drawings constituting a part hereof in which like reference characters designate like parts and in which:

Fig. 1 is a top plan view of a railway switch assembly embodying the principles of this invention;

Fig. 2 is a vertical cross-sectional view extending longitudinally of the switch along the line 2—2, Fig. 1;

Fig. 3 is a transverse section taken through the switch unit along the lines 3—3, Fig. 1;

Fig. 4 is a cross-section of a portion of the switch housing diagrammatically illustrating its relation to the switch element;

Fig. 5 is a sectional elevational view of a portion of the locking mechanism;

Fig. 6 is an exploded view of the switch unit and rail to illustrate the manner of the connection;

Fig. 7 is a view in perspective partially in cross-section of a portion of the switch and locking mechanism; and

Fig. 8 is a sectional elevational view taken 53

through the switch unit along the line 8—8, Fig. 1.

With reference to Figs. 1 and 2 of the drawings, the structure therein illustrated comprises a base 1 supported on rail ties 2 having depending lugs 3 for engagement with the ties, the base having upwardly extending bearing blocks 4 provided with dove-tail slots 5 constituting guideways for dove-tails 6 depending from the movable switch blocks 7 and 7a. By this construction the switch blocks 7 and 7a are solidly supported on the base members 1 and positively secured against longitudinal movement relative to the rails which are the main rails 8 and 8a and the turn-out rails 9 and 9a. The rail blocks 7 and 7a are provided with depending portions 10 disposed intermediate the base bearing blocks 4, the members 10 being shaped as shown in Figs. 3 and 7, similar to the web and base of a rail and being preferably integrally formed with the switch blocks 7 and 7a.

Flange grooves 11, 12, 13 and 11a, 12a and 13a are provided in the rail blocks 7 and 7a, the grooves 13 and 13a being on angles corresponding to the turn-out angle of the switch.

A plurality of stop lugs 14 and 15 are disposed on the sides of the base members 1 and in one position are adapted to abut the depending portions 10 of the switch blocks. Lugs 14 and 15 are disposed in channels 16 and 16a in which they are freely slideable, the channels being integrally formed with the base 1 as shown in Figs. 3 and 7. Lugs 14 and 15 are slideable in the channels 16 and 16a by a mechanical linkage comprising links 17, levers 18 and 19 and slide bars 20, the bars 20 being actuated by a bar 21, disposed in guide brackets 21a, which is provided with cam followers 22 disposed in cam slots 23, so that in response to movement of bar 21 transversely of the rails, the slide bars 20 will be subjected to sliding movement. Movement of the bars 20 actuates levers 18 and 19 which in turn subject the lugs 14 and 15 to sliding movement in the channels 16.

As shown in Fig. 7, the dove-tail 5 is located above the latch lug 15, and its operating linkage 17, so that the switch block clears the lugs 15 when thrown beyond the bearing block 4, and the channel 16 in which the latch lugs 15 are operative is below the sliding base of the depending portion 10 of the switch block. The dotted line construction of the lug 15, Fig. 7, shows the lugs extended to the position where the depending portion 10 of the switch block is engaged.

The switch blocks 7 and 7a are connected by links 24 to render them simultaneously movable by a throw-bar 25, the bars 21 and 25 as shown in Fig. 3 being actuated by cams 26 and 27, respectively, the cams being mounted to rotate with a shaft 28 that is actuated by a hand lever 29 or in any other suitable manner. Each of the cams is provided with a cam slot for engaging followers 30 and 31 carried by the cams, so that upon rotation of shaft 28 the bars are subjected to linear movement. The connected switch blocks 7 and 7a are subjected to shuttle movement as distinguished from the swinging or pivotal movement of the conventional type switch.

One of the features of the invention is the elimination of switch points which permits interlocking the rails with the switch base, it being understood that there is no base plate if switch points are employed, and consequently there can be no interlocking of the switch parts and main track. As shown in Fig. 6 the end of the base 1 is slotted at 32 to receive the web 33 of the end of the rails, the base of the rail being cut-out as shown to allow the web portion to enter the slot 32. The rail may be fastened in the slot by any suitable means, although this may not be deemed essential. As shown in Fig. 4 the switch blocks 7 and 7a may be provided with aprons 34 and 35 which are secured at the ties by bottom flanges 36 as shown.

Fig. 7 illustrates the structural features of the switch base and switch block which permits free sliding movement of the block and the base provides a large area of bearing contact and locks the switch block in its extended position. It shows the depending rail switch block portions resting on the face of the base between the upwardly extending bearing portions 4.

The operation of the above-described railway track switch is briefly as follows: In the position shown in Fig. 1 the switch is set for the main or straight track 8 and 8a with the flange grooves 11 and 11a in alignment therewith, so that the wheel flanges ride in the grooves and the adjacent top surface constitutes the rail for the wheels. It is locked in this position by the movable lugs 15 and fixed stops 7c which constitute abutments for the switch block 7. Also it will be noted that in this position the flange grooves 12 and 12a are in alignment with the turn-out track 9 and 9a so that if a railway vehicle passes over the switch from the turn-out track when it is set to the main rail position, it will not derail but will pass through the groove into the flange grooves 11 and 11a. To throw the switch to the turn-out track position lever 29 is manipulated in a downward direction as viewed from the base of the drawings, thereby actuating the shaft 28 on which cams 26 and 27 are mounted. The relation of the cam slots is such that the switch bar 25 will move switch blocks 7 and 7a in the direction to align the flange grooves 13 and 13a with the inside faces of the turn-out rails 9 and 9a and cam 26 will then actuate the locking bar 21 to actuate the levers which project the lugs 14 outwardly into the space between the bearing blocks 4 to constitute abutments for the depending rail block portions 10, thereby securely holding them to the set position of the switch. The cam 26 for actuating the locking bar 21 and the cam 27 for actuating the throw arm 25 are so arranged that, upon initial movement of lever 29, cam 26 will actuate locking bar 21 to release the locks 14 or

15, as the case may be. Upon further rotation of lever 29, the throw bar 25 will move slide blocks 7 and 7a to the other position, and upon still further rotation of lever 29 cam 26 will actuate the locking bar 21 to again bring locks 14 or 15, as the case may be, in abutting engagement with their corresponding slide block. Upon reversal of the operation, the same sequence of unlocking, throwing and locking is effected.

As shown in Fig. 1, switch blocks 7 and 7a are provided with stops 7b and 7c which are adapted to engage the bearing blocks 4 of the base. When the switch is thrown to either straight or turn out rail position the stops 7b or 7c of one block will abut the bearing blocks 4 of its cooperating base and the lugs 14 or 15 on the base will abut the depending portions 10 of the switch block thereby locking the latter against transverse movement in either direction.

Fig. 1 shows the switch set in line with the tangent track rails 8, 8a. In this position, as shown in Fig. 8, the stop 7b abuts bearing block 4 of switch block 7a and the depending portion 10 of the switch block 7 is locked by lugs 15. The locking lugs 14 are beneath the switch block 7a, as shown in Fig. 1, and when the switch is thrown for alignment with the turn-out rails 9 and 9a, the stop 7c engages bearing block 4 with stop 7b clear, and the locking lugs 14 abut the depending portion of switch block 7a while the lugs 15 are beneath the bearing block 7. The manipulation of the switch blocks from the tangent to the turn-out position and the operation of the lugs 14 and 15 will now be explained with reference to Figs. 1, 3 and 8 of the drawings.

With the switch in tangent position, switch lever 29 is turned to rotate cams 26 and 27, the former operating latch bars for actuating the lugs 14 and 15 and the latter operating to move the switch blocks 7 and 7a, as shown in Fig. 1, the pin 22 of the bar 20 that actuates the latch lugs 15 being in the end of the slot of the bar 21, in which position the operating bar 20 holds lugs 15 against the depending portion 10 of the switch block 7. Therefore, upon initial movement of the switch lever 29, cam 26 will move the bar 21 to retrieve bar 20 by movement of the pin 22 in the straight portion of the slot. This movement retracts the latch lugs 15 to clear the switch block 7.

Further movement of the lever 29 actuates the bar 25, which throws the switch, causing switch block 7 to pass over latch lugs 15 until the stop lug 7c abuts the bearing block 4 of the switch block 7. At the same time, because of the connecting links 24, switch block 7a moves in the direction to clear abutting lug 7b, and the latch lugs 14 are clear of the depending portion 10 of block 7a. When the pin 22 has moved to the offset position of slot 23 at the end of travel of bar 21, the operating bar 20 will force the latch lugs 14 forward to engage the depending members 10 of switch block 7a, thereby locking the switch in the set position with stop lugs 7c abutting the bearing block 4 of switch block 7.

The aprons 34 and 35 cover the operating mechanism including the levers and actuating links for the locking lugs so as to prevent ingress of loose particles such as stone or the like and also to protect the operating mechanism and the bearings from the corrosive action of the elements. These aprons prevent snow and sleet from entering the switch operating mechanism,

thus keeping them clear for operation at all times. By means of the locking lugs which are operative in response to the switch setting mechanism, the switch is locked in set position and is entirely stable, both longitudinally and transversely of the rails.

There are no parts to be injured by contact of the vehicle wheels passing over the switch blocks 7 and 7a and because of the locking lugs, displacement of the switch with consequent derailment is eliminated.

It will be noted that the point of switch designated by numerals 13b and 13c is placed some distance within the switch block so that the wheel can enter upon the switch block in a straight line for both the main and turn-out tracks and in the turn-out side the wheel flange will be well within the flange groove of the switch block before beginning the turn.

The cam actuated slide bars are positive in their action and the aprons housing the switch and operating parts assures that they are free from interference to prolong and maintain their efficient operation.

It is believed to be apparent that the solid cast steel base and the massive switch blocks with their interacting dove-tailed engagement and substantial supporting and contacting areas render the switch as substantial and stable as the rail itself, there being no possibilities of displacement of any of the switch parts relative to the rails as the elimination of the switch points permits a construction which intimately engages the end of the rails with the switch castings.

Although one embodiment of the invention has been herein illustrated and described, it will be apparent to those skilled in the art that various modifications may be made in the details of construction without departing from the principles herein set forth.

I claim:

1. A railway switch comprising a base member having upstanding bearing blocks, switch members recessed to receive said bearing blocks and having bearing portions for engagement with the base intermediate said bearing blocks whereby said switch members are adapted for sliding movement on the base transversely of the axis of the base and positively held against displace- 50

ment in a longitudinal direction, said switch members having wheel engaging faces extending from end to end of said members and adapted for register with a pair of main and turn-out tracks, movable stops in the base member adapted to extend in the path of movement of the switch members, means for actuating said stops, a switch bar and a locking bar, the latter connected to actuate said stop actuating means, a plurality of cams connected to said bars mounted for simultaneous operation, whereby the locking means is coordinated with the switch operating means.

2. A railway switch comprising a plurality of base members having depending ribs spaced to engage rail ties therebetween and having upwardly projecting bearing blocks with guideways formed therein, a plurality of switch blocks recessed to receive the bearing blocks of the base members and having guide means for cooperative engagement with the guideways of said bearing blocks, said switch blocks having downwardly depending portions for engaging bearing surfaces of said base members between the bearing blocks thereof and having abutments for engaging the bearing blocks, means adapted to be interposed in the path of movement of said downwardly depending portions of the switch blocks to constitute locking abutments for said switch blocks, means for subjecting the switch blocks to movement transversely of the main and turn-out rails, and means for coordinately moving the switch block abutting means with switch block moving means.

3. A railway switch comprising a plurality of base members adapted for mounting on rail ties and having bearing blocks with guideways formed therein, a plurality of switch blocks having guide means in cooperative engagement with the guideways of said bearing blocks and having fixed abutments for engaging the bearing blocks of said base members, movable abutments mounted on said base members in the path of movement of said switch blocks, means for subjecting the switch blocks to movement transversely of a main and turn-out rail, and means for coordinately actuating the movable switch block abutting means with said switch block moving means.

CHARLES L. WILMOT.
